VALVE FOR WELL PUMP RODS

William John Wranosky, Freer, Tex.

Application February 1, 1938, Serial No. 188,161

1 Claim. (CL 103—229)

The present invention relates to valves for the pump rods of oil wells and the like and has for its primary object to provide an automatic pressure actuated valve carried by the pump rod above the piston or plunger and arranged for opening movement upon the upstroke of the plunger and embodying means for automatically closing the valve upon the down stroke of the plunger to relieve the plunger of the weight of the fluid in the tube above the valve during said downstroke.

An object of the present invention is to provide a valve structure of this character of simple and practical construction, which is efficient and reliable in performance, relatively inexpensive to manufacture and install in operative position within the well casing and otherwise well adapted for the purposes for which the same is intended.

Other objects and advantages reside in the details of construction and operation as more fully hereinafter described and claimed, reference being had to the accompanying drawing forming part hereof, wherein like numerals refer to like parts throughout and in which

Figure 1 is a fragmentary vertical sectional view through a pump tubing showing the valve in position therein,

Figure 2 is a transverse sectional view taken substantially on the line 2—2 of Figure 1 and Figure 3 is a side elevational view of the valve and sleeve mounted upon the pump rod.

Referring now to the drawing in detail, the numeral 5 designates a well tubing within which the pump rod 6 is mounted for operation in the usual manner, the lower end of the pump rod having the usual plunger attached thereto for forcing the fluid upwardly through the tubing.

The present invention comprises a sleeve 7 having a snug working fit upon the rod 6, said sleeve and rod being slidably inserted in an opening 8 in the upper end of a cage 8. The cage is spaced outwardly from the sleeve 7 and is provided with vertically extending slotted openings 10 by means of which fluid is adapted to pass upwardly through the cage to the upper portion of the tubing.

To the lower end of the cage 8 is threaded a valve body 11 having a bore 12 extending therethrough, the upper end of said bore being of increased diameter to provide a shoulder 13 upon which a valve seat 14 is positioned. A substantially conical valve 15 is invertedly arranged and threaded to the lower end of the sleeve 7 for cooperation with the valve

seat 14 to close passage through the bore 12, said valve being provided with a central opening 16 through which the rod 6 is slidably inserted. The upper portion of the valve is provided with an annular channel 17 within which is seated the lower end of a coil spring 18, the upper end of said spring bearing against the top of the cage to yieldably urge the valve downwardly into engagement with the seat 14.

The upper edge of the sleeve 7 is bevelled as 19 to provide a knife like edge 20 which bears against the rod 6 to scrape sand from the rod during the reciprocating movement thereof. The lower portion of the valve body 11 is provided with annular grooves 21 for receiving packing rings 22 in order to anchor the cage in the tubing.

In the operation of the device upon the upstroke of the plunger attached to the lower end of the rod 6 the valve 15 will be forced open to allow the fluid to pass upwardly through the cage to the upper portion of the tubing 5 and upon the downstroke of the piston and rod 6 the spring 18 will serve to close the valve, and the fluid accordingly will be retained above the plunger in the upper portion of the tubing.

It is believed the details of construction and manner of operation of the device will be readily understood from the foregoing without further detailed explanation.

What is claimed is:

A valve for the pump rod of an oil well comprising a sleeve having a working fit upon said rod, a valve cage having an opening in its upper portion slidably receiving said sleeve, said cage being spaced from the sleeve and having openings for the passage of fluid through the cage, a valve body threaded to the lower end of said cage, packing means surrounding the valve body and engaging the tubing of the well, a valve seat carried by said body, a valve threaded to the lower end of said sleeve and arranged in cooperating engagement with said valve seat, said valve having an opening for the passage of the rod, said valve being responsive to pressure below the valve for opening movement, a spring surrounding the sleeve and having one end engaging the valve and its other end engaging the top of the cage for holding the valve upon the seat and the upper end of the sleeve being beveled for scraping foreign matter from that part of the rod which it engages.

WILLIAM JOHN WRANOSKY.
